UNITED STATES PATENT OFFICE.

NATHAN RUBENSTEIN, OF NEW YORK, N. Y.

MACHINE FOR FACILITATING THE UNROLLING OF CLOTH FROM CLOTH BOLTS.

1,300,655.

Specification of Letters Patent. Patented Apr. 15, 1919.

Application filed May 3, 1918. Serial No. 232,253.

To all whom it may concern:

Be it known that I, NATHAN RUBENSTEIN, a citizen of the United States, and a resident of New York, borough of Bronx, in the county of Bronx and State of New York, have made and invented certain new and useful Improvements in Machines for Facilitating the Unrolling of Cloth from Cloth Bolts, of which the following is a specification.

My invention relates to machines designed particularly for use by manufacturers of clothing and in similar trades, the purpose thereof being to provide a machine whereby cloth may be readily unwound from the cloth bolt or roll in which it is ordinarily sold and laid upon a table preparatory to cutting the garment or other article to be produced therefrom, by the use of a suitable pattern; the usual practice in the manufacture of clothing or other articles from cloth being to unroll the cloth from a bolt or roll and pile it in several thicknesses upon a table, after which a plurality of pieces from which the garment or other article is formed are cut out at a single time from the pile of cloth thus accumulated.

The object of my invention is to provide an improved machine of the type or class above referred to and for the purpose pointed out in which the cloth bolt or roll is supported and held in a vertical position while the cloth is being unrolled, and in which the bolt or roll may be easily removed from the machine and another substituted therefor, should occasion arise for the use of another kind of cloth. More particularly stated, my invention contemplates and the object thereof is to provide a cloth unwinding machine in which a readily removable portion of the machine is designed to remain within the bolt or roll until the cloth is all used therefrom; the machine in question being commonly provided with a plurality of such removable portions which remain within the bolt, in order to provide for the use of different kinds of cloth from different bolts or rolls, and for the interchange of bolts or rolls with a minimum of delay and inconvenience. It will, however, be appreciated that a given machine made in accordance with my invention may be provided with one only of the removable elements which enter into and serve to hold the bolt or roll in an upright position, in case cloth all of one kind is to be used.

A further object of my invention is to pro-

vide a cloth unwinding or unrolling machine of the type or class above referred to which will be simple in construction and easily portable, so that it may be placed in proximity 60 with the table or other support upon which the cloth is laid preparatory to being cut into suitable shapes from a pattern; the said machine being simple in construction, easy to manufacture, and effective for the purpose 65 for which it is designed.

With the above and other objects in view, my invention consists in the machine for facilitating the unwinding or unrolling of cloth from the bolt or roll illustrated in its 70 preferred form in the accompanying drawings, described in the following specification, and particularly claimed, and in such variations and modifications thereof as will be obvious to those skilled in the art to which 75 my invention relates.

The drawings accompanying and forming a part of this specification illustrate what I regard as the preferred embodiment of my invention, the same being shown in two 80 forms, differing somewhat from each other, so far as concerns the manner in which the machine is supported from a suitable support; although it will be appreciated that my invention may be embodied in various other 85 specific forms, and that the same includes all such embodiments thereof as come within the scope of the concluding claims wherein the particular features in which my invention consists are particularly pointed out. 90

Referring to the drawings:

Figure 1 is a view illustrating my improved cloth unwinding machine in plan, and attached to a suitable table;

Fig. 2 is a view showing a section of the 95 same taken upon a vertically-extending plane indicated by the line 2—2 of Fig. 1;

Fig. 3 is a view showing in side elevation a modified form of the element of the machine used to hold the cloth bolt in an up- 100 right position;

Fig. 4 is a perspective view illustrating a form of my invention in which a different form of supporting member or base for supporting the machine is employed; and 105

Fig. 5 is a fragmentary view illustrating certain features of the form of my invention illustrated in Fig. 4 upon a larger scale, and more in detail, than in said figure.

Referring first to the embodiment of my 110 invention illustrated in Figs. 1 and 2, the same is shown as comprising a suitable sup-

porting member or base 7 designed to be clamped to a table 8 by means of a screw 9, the upper portion of said supporting member being hollow as indicated at 10, and 5 having two bearings 11, 12, spaced apart and arranged one above the other as shown; the upper of these bearings 12 being preferably in the form of a removable bushing in threaded engagement with the upper end 10 of the opening 10, in order that the supporting shaft to be hereinafter referred to may be readily assembled with the base and held in proper position in the machine.

The reference numeral 13 designates a 15 horizontally arranged table rotatable about a vertical axis, which table is supported from and above the supporting member 7 and in turn serves as a support for the cloth bolt or roll from which the cloth is to be 20 unwound; the supporting of the table being illustrated as accomplished by the use of a vertically extending shaft 14 rotatable in the bearings 11, 12 above referred to, and which shaft extends upward through the 25 table and to some little distance above the upper surface thereof, as best shown in Fig. 2. The table 13 is shown as in threaded engagement with the shaft at 15, so that the two rotate together; and a nut 16 is provided which is in threaded engagement with the shaft and serves, in the embodiment of 30 my invention illustrated, to hold the table and shaft together in a rigid and permanent manner. The shaft 15 is provided with an 35 opening adapted to receive a transversely extending pin 17, which pin, when the parts are assembled, lies in close proximity with the lower end of the bushing 12 and thus holds the shaft in proper position within 40 the bearings aforesaid and relative to the supporting member or base. It will be appreciated, however, that the details of the manner in which the rotating table is supported from the supporting member may be 45 varied considerably without departing from the spirit of my invention, as the same is pointed out and defined in the claims at the end of this specification.

The reference numeral 18 designates as a 50 whole a vertically extending bolt supporting member supported from the table 13 and extending upwardly therefrom, and adapted to enter a cloth bolt 19 between the inner layer of cloth and the board 20 upon which 55 the cloth is wound, as shown in Figs. 1 and 2; the purpose of the said supporting member being to hold the cloth bolt in an upright position, so that the same may rotate about a vertical axis in unwinding the cloth. 60 This bolt-supporting member is shown as made up of two portions, the upper of which is in the form of a spindle 21, while the lower portion is in the form of a hollow sleeve 22; whereby a longitudinally extending 65 passage is provided at the lower end

of the bolt supporting member into which the free upper end of the shaft 14 enters. The lower end of the bolt supporting member, or rather of the sleeve 22, rests upon and is supported by the table 13, a flange 23 70 being preferably provided at the lower end of the sleeve in order to provide an extended bearing surface and a steadier support for the cloth bolt or roll.

It will be appreciated that the features of 75 construction of the bolt supporting member above described provide a scheme in which the cloth bolt, together with the bolt supporting member contained within the same, may be readily removed from the supporting 80 table and a new bolt of another kind of cloth and having another bolt supporting member within the same substituted therefor; thus providing for the interchange of 85 cloth bolts, and for the use of various kinds of cloth, according to the requirements of the user, with a minimum of trouble and expense and by the use of a single machine equipped, however, with a plurality of interchangeable bolt supporting members.

The upper end of the bolt supporting member illustrated in Figs. 1 and 2 is shown as provided with a steadyng member 24, shown as in the form of a ring, although the form of steadyng member is of secondary importance; the purpose of this member being to prevent the bolt from tipping, or, as otherwise expressed, to hold the central spindle portion of the bolt-supporting member centrally within the cloth-bolt; it being appreciated that were this element not employed the upper end of the bolt supporting member might tend to move laterally along the board 20 to one edge or the other thereof, which would result in a wabbling 105 motion of the bolt as the cloth was unwound, and might otherwise interfere with the unrolling of the cloth.

Fig. 3 shows a form of bolt supporting member interchangeable with the table and shaft shown in Figs. 1 and 2, this form of supporting member being especially adapted for use in unwinding cloth or similar fabric from a circular bolt, *i. e.*, one in which the fabric is found about a tube instead of 110 about a board; the said supporting member being made up of a spindle 25 having a hollow sleeve 26 whereby a longitudinally extending opening is provided at the lower portion thereof, and the lower end of which 115 sleeve is provided with a flange 27; the construction of bolt supporting member here illustrated being similar to that illustrated in Figs. 1 and 2, except that the steadyng member is omitted.

Fig. 4 illustrates a form of my invention in which a form of supporting member or base different from that illustrated in Figs. 1 and 2 is employed, the form of base illustrated in this figure being designed to rest 130

upon a table, or shelf, or even upon the floor, without, however, being clamped to the member upon which it rests.

In this form of my invention, the rotating table 28 and vertically extending cloth bolt supporting member or spindle 29 are or may be of the same form and construction as the table and spindle hereinbefore referred to in describing the embodiment of my invention illustrated in Figs. 1 and 2. The vertically extending shaft 30, which carries the table 28, is also shown as of the same form as hereinbefore described, the lower end thereof being illustrated as supported in spaced bearings 31, 32, provided in a suitable base 34, the upper of said bearings being in threaded engagement with the upper end of an opening 33 provided in the base whereby the machine as a whole is supported, the shaft being held in place by means of a transversely extending pin 35, as hereinbefore explained.

In the embodiment of my invention illustrated in these figures, the base 34 is formed as a single casting and is provided with a plurality of radially extending arms 36 having feet 37, made preferably of rubber, at their extremities, whereby the base is prevented from slipping. The form of base described obviously provides an extended support for the table 28 and cloth bolt supported thereby, and thus provides a somewhat more stable machine than that illustrated in Fig. 1, and at the same time provides a machine which may be conveniently moved about from one place to another, as it is not necessary to clamp the same to a table or other support preparatory to using the machine, as is the case in the embodiment illustrated in Figs. 1 and 2.

The radially extending arms 36 of the base are shown as and are preferably provided each with a roller 38 supported in suitable bearings 39, and the peripheries of which rollers are adapted to engage with the under side of the table 28, whereby the same is prevented from tipping and is somewhat more steadily supported; as it will be obvious that there is commonly more or less looseness and lost motion between the vertically extending shaft 30 and the bearing in the base in which it is supported, which looseness, however, is counteracted by the rollers and a more steady support for the table thus secured, as will be appreciated.

Having thus described and explained my invention, I claim and desire to secure by Letters Patent:

1. In a device of the class described, a suitable supporting member or base; a vertically extending rotatable shaft carried by said supporting member; a horizontally arranged table carried by said shaft; a vertically extending spindle adapted to enter a cloth bolt and having a passage formed in

its lower portion adapted to receive the upper end of said shaft, and a flange at its lower end adapted to rest upon said table, and a steadyng member carried by and located adjacent the upper end of said spindle. 70

2. In a device of the class described, a suitable supporting member or base having two spaced bearings arranged one above the other and the upper of which is removably secured in a recess provided in said base; a vertically extending shaft rotatable in said bearings; a horizontally arranged table carried by and rotatable with said shaft; and a bolt supporting member extending upward from said table and adapted to enter a cloth bolt and hold the same in an upright position. 75 80

3. In a device of the class described, a suitable supporting member or base having two spaced bearings arranged one above the other; a vertically extending shaft rotatable in said bearings; a horizontally arranged table carried by and rotatable with said shaft; and a vertically extending bolt supporting member adapted to enter a cloth bolt and having a passage formed in its lower portion adapted to receive the upper end of said shaft, and a flange at its lower end adapted to rest upon said table. 90 95

4. In a device of the class described, a suitable supporting member or base; a horizontally arranged rotatable table supported from said supporting member; a vertically extending shaft carried by said supporting member and extending through said table; and a vertically extending bolt supporting member adapted to enter a cloth bolt and having a passage formed in its lower portion and adapted to receive the upper end of said shaft, and the lower end of which bolt supporting member rests upon said table. 100 105

5. In a device of the class described, a suitable supporting member or base having two spaced bearings arranged one above the other; a vertically extending shaft rotatable in said bearings; a horizontally arranged table secured to and rotatable with said shaft; a bolt supporting member extending upward from said table and adapted to enter a cloth bolt and hold the same in an upright position; and a plurality of rollers carried by said supporting member or base, and the peripheries of which are adapted to engage the under side of said table. 110 115 120

6. In a device of the class described, a suitable supporting member or base; a horizontally arranged rotatable table supported from said supporting member; a vertically extending shaft carried by said supporting member and extending through said table; a vertically extending bolt supporting member adapted to enter a cloth bolt and having a passage formed in its lower portion and adapted to receive the upper end of said 125 130

shaft, and the lower end of which bolt supporting member rests upon said table; and a plurality of rollers carried by said supporting member or base, and the peripheries of which are adapted to engage the under side of said table.

Signed at New York, borough of Manhat-

tan, in the county of New York and State of New York, this second day of May, A. D. 1918.

NATHAN RUBENSTEIN.
